UNITED STATES PATENT OFFICE

ARTHUR F. DONOVAN, OF HARTFORD, CONNECTICUT

DESIGN FOR A DRESS BUCKLE OR SIMILAR ARTICLE

Application filed June 24, 1932. Serial No. 44,177. Term of patent 7 years.

To all whom it may concern:

Be it known that I, ARTHUR F. DONOVAN, a citizen of the United States, residing at Hartford, in the county of Hartford and State of Connecticut, have invented a new, original, and ornamental Design for a Dress Buckle or Similar Article, of which the following is a specification, reference being had to the accompanying drawing.

Of the drawing:

Fig. 1 is a front view of a dress buckle or similar article embodying my invention.

Fig. 2 is a side view.

Fig. 3 is a central sectional view.

I claim:

The ornamental design for a dress buckle or similar article as shown.

ARTHUR F. DONOVAN.
